M. ROSEN.
SANITARY WATER CLOSET SEAT.
APPLICATION FILED OCT. 27, 1916.

1,215,197.

Patented Feb. 6, 1917.

UNITED STATES PATENT OFFICE.

MAX ROSEN, OF PHILADELPHIA, PENNSYLVANIA.

SANITARY WATER-CLOSET SEAT.

1,215,197.

Specification of Letters Patent.

Patented Feb. 6, 1917.

Application filed October 27, 1916. Serial No. 128,000.

To all whom it may concern:

Be it known that I, MAX ROSEN, a citizen of the United States, residing in the city and county of Philadelphia, State of Pennsylvania, have invented a new and useful Sanitary Water-Closet Seat, of which the following is a specification.

My invention consists of a water closet seat which is made sanitary by the application thereto of a disinfectant or similar material successively to the two surfaces of the seat, so as to present a freshly disinfected seating surface to the occupant.

To this end I employ a seat proper and a channeled or gutter-like member which is adapted to receive material as aforesaid, into which the portion of the seat that is below is adapted to dip, and said seat is reversible so as to bring the freshly-disinfected portion to the top for occupation in said condition.

The invention is satisfactorily illustrated in the accompanying drawing, but the important instrumentalities thereof may be varied, and so it is to be understood that the invention is not limited to the specific details shown and described.

Figure 1 represents a perspective view of a sanitary water closet seat embodying my invention, the seat proper thereof being raised.

Fig. 2 represents a diametrical section thereof on an enlarged scale, the seat proper being closed.

Fig. 3 represents a transverse section thereof on line 3—3 Fig. 2.

Fig. 4 represents a plan view of the disinfectant-holding member employed.

Fig. 5 represents a partial side elevation and partial vertical section, on an enlarged scale, of the connecting devices of the seat proper and the channeled member employed.

Fig. 6 represents a top or plan view thereof.

Fig. 7 represents a plan view of a portion of the seat.

Similar numerals of reference indicate corresponding parts in the figures.

Referring to the drawings.

1 designates the seat or seat proper of a water closet, the same being formed preferably of wood, as well known. 2 designates a guttered base formed of particularly metal or other suitable material of substantially of the contour of the seat, and whose

opening 3 is in register with the opening 4 of the seat.

In the bottom of the gutter 5 of the base 2 is the depressed channel 6 in which is seated the cord, batting, or wicking 7 of fibrous material which in order to be retained in the channel is inclosed in a sheath 8, such as a coil of wire, or some suitable tubing which weighs said wicking, it being noticed that the gutter of the base 2 is adapted to receive a disinfectant, and that the under portion of the seat is adapted to enter the gutter, and so be subjected to the action of the disinfectant.

The rear of the seat 1 is connected with the rear of the base 2 by a hinge that renders the seat reversible, hence after it has been occupied and used it may be turned so as to bring the face of the portion of the seat in the gutter to the top and so present a freshly disinfected surface of the seat to the next occupant, while when as the seat is lowered the surface that was above enters the gutter and so is subjected to the disinfectant therein, and so by raising, reversing and lowering the seat, the disinfection of the two surfaces of the seat may be continued.

The hinge of the seat and base consists of the cup or socket 9 which is secured to the base 2, and the pin 10 whose head occupies the interior of said cup and forms with said cup a ball and socket joint. In the crown of the socket is an opening through which is passed the shank 11 of the pin 10 whereby said cup 9 may turn on said shank so that the reversal of the seat may be accomplished.

The shank 11 is threaded and fitted in a threaded opening in the arm or hanger 12 whose upper end is pivotally connected as at 13 with ears 14 which rise from the plate 15, the latter being secured to the rear portion of the base by the screws 16 or other suitable means.

It will be seen that the seat may be drawn forward the arm 12 swinging forward on its pivot 13 and describing an upward axial motion, whereby the seat is raised clear of the base as shown in Fig. 1. Then the seat may be reversed and lowered and moved rearwardly with the arm 12 and so placed over the gutter 5 and lowered into the base, the seat then being adapted to be occupied as usual.

The rear of the base has connected with it

the butts or leaves 18 of hinges for connecting the base with a bowl or the frame of the box thereof, whereby both the base and seat may be raised as one for access to the interior of the bowl and then lowered in operative position.

The channel 6 particularly is adapted to contain the disinfectant which will be absorbed in part by the wicking 7, and so 10 passed off therefrom as to reach the underside of the seat to apply the same thereto.

On the inner and outer edges of the seat 1 are the gaskets 17 which are inserted into said edges and so secured in position, they 15 being so disposed that when the seat is in lowermost position they abut the top wall of the gutter 5 forming means for sealing the latter and preventing the escape of the disinfectant therat.

20 The material employed as a disinfectant or germicide will be preferably of a fluid nature so as to be absorbed by the batting or wicking 7, and its vapors or fumes passed off therefrom to the underside of the seat 25 to render the same of the sanitary nature as hereinbefore stated.

The sheath 8 with its inclosed absorbent material 7 is retained in the gutter 5 by the straps 19 which are placed over the 30 former and secured to the adjacent wall of the gutter 5, as most plainly shown in Figs. 1 and 2.

Having thus described my invention, what I claim as new and desire to secure by Letters Patent, is:—

1. A sanitary seat for a water closet comprising a guttered base adapted to contain material of a sanitary nature, a seat proper which is adapted to enter said base, a swinging arm which is pivotally mounted on a member rising from said base, and a ball and socket like joint, the members of which are connected respectively with said seat and arm adapting said seat proper to be raised 40 and lowered from and to said base and reversed, and present either of the faces of said seat proper for occupation above, and either face into said base.

2. In a sanitary seat for a water closet, a

base provided with a gutter and a channel 50 below said gutter in communication therewith, said channel being adapted to contain material of a sanitary nature, and a seat proper adapted to be raised and lowered and reversed and have either of its faces enter said 55 gutter, said channel having therein a piece of absorbent for said material, and an open sheath around said piece adapted to weight the same.

3. A sanitary seat for a water closet comprising a guttered base adapted to contain material of a sanitary nature, a seat proper which is adapted to enter said base, a swinging arm, a bearing on said base for said arm, a ball and socket like joint, the members of 65 which are connected respectively with said seat and arm adapting said seat proper to be raised and lowered from and to said base and reversed, and present either of the faces of said seat proper for occupation above, 70 and either face into said base, and means on said base adapting the combined base and seat proper for connection with the closet adapting them to be raised and lowered as one respectively from and to the closet bowl. 75

4. In a sanitary seat for a water closet, a base provided with a gutter adapted to contain material of a sanitary nature, and a seat proper adapted to be raised and lowered and reversed and have either of its faces enter said gutter, the latter having therein a piece of absorbent for said material, said gutter having in its lowered portion a channel adapted to contain said piece of absorbent 80 therein.

5. In a sanitary seat for a water closet of the character stated composed of a guttered base, a seat proper adapted to enter said base, a hanger arm pivotally mounted on a member rising from said base, and a ball 90 and socket like joint having its members adapted to be connected respectively with said seat and arm.

MAX ROSEN.
